COMBINED HAIR ROLLER TRAY AND STAND

Kenneth Reiner, P.O. Box 54091, Terminal Annex,
Los Angeles, Calif.

Filed Apr. 10, 1964, Ser. No. 79,436

Term of patent 14 years

(Cl. D86—10)

FIG. 2.

I claim:

The ornamental design for a combined hair roller tray and stand, as shown.
